Geo. F. Kimmel.

ATTORNEY.

UNITED STATES PATENT OFFICE.

JAMES S. PATTERSON, OF ABILENE, TEXAS.

CAN OPENER.

Application filed November 12, 1926. Serial No. 147,993.

The invention relates to a tool designed to permit the opening of cans, and the removal of bottle caps, and more particularly to the class of can openers.

5 The primary object of the invention is the provision of a tool or opener of this character, wherein a can can be readily and conveniently opened, by cutting into the top to partially or completely remove the same, the
 10 tool or opener being of novel form, so that the cutting element can be reversely operated, and its runner adjusted, whereby the can top can be cut either in one direction or the other, as the parts of the tool or opener
 15 are readily adjustable to effect the operation of the same in either direction.

Another object of the invention is the provision of a tool or opener of this character, wherein the runner supporting the cutting
 20 element can be adjusted so that it can be utilized to remove caps from bottles, in a convenient and simple manner with dispatch.

A further object of the invention is the provision of a tool or opener of this character, wherein the parts thereof are connected
 25 together to constitute a unit, yet the same are readily adjustable, one relative to the other, so as to permit the tool or opener to be reversely operated, or its utilization as a bottle
 30 opener.

A still further object of the invention is the provision of a tool or opener of this character, which is extremely simple in construction, thoroughly reliable and efficient in its
 35 purpose, possessing of but few parts, strong, durable, capable of operation with dispatch to open a can or other container and inexpensive to manufacture.

With these and other objects in view, the invention consists in the features of construction, combination and arrangement of parts as will be hereinafter fully described in detail, illustrated in the accompanying drawing, showing the preferred embodiments of
 45 the invention, and pointed out in the claim hereunto appended.

In the accompanying drawing:

Figure 1 is an elevation of the tool or opener constructed in accordance with the invention, shown and arranged relative to a can or receptacle for the opening thereof, the can being fragmentarily illustrated by dotted lines.

Figure 2 is a view similar to Figure 1 looking toward the tool in edge elevation.

Figure 3 is a fragmentary plan view, show-

ing portions of the tool broken away and the latter in position relative to the can top.

Figure 4 is a side elevation of the tool or opener as shown applied to a bottle for the removal of its cap therefrom, a portion of the tool being broken away to disclose details.

Similar reference characters indicate corresponding parts throughout the several views in the drawing.

Referring to the drawing, in detail, the tool or opener comprises a runner A formed from a single length of material of strip form, preferably made from metal, bent on itself to provide a segmental shaped frame 5 having an inner relatively long stretch 6 and an outer relatively short stretch 7, providing therebetween a segmental slot 8 coextensive with the length of the shorter stretch 7. The stretch 7 is of materially less length 75 than the length of the stretch 6 and has its free end terminate an appropriate distance from the free end of the latter. The free end of the stretch 6 is provided with a laterally extending, outwardly projected, curved ear 80 9 having its free end providing a wide bearing for the inner face of a can rim. The stretch 7 has integral with its free end an outturned, angle-shaped projection 10 formed of an inner and an outer arm, is spaced a 85 substantial distance from the ear 9 and constitutes a guide and a fulcrum and further serves as a claw or jaw for coupling the frame to the can rim. The inner arm of the projection 10 is of less width than the outer 90 arm thereof and provides in connection with the stretch 6 a pair of grooves 11 to constitute seats for the rim 12. The rim 12 when engaged in one of the seats formed by the grooves 11 will position the frame 6 in the 95 manner as shown in Figures 1 and 2.

The outer arm of the projection 10 serves as an abutment for the rim 12 of the can body B to hold the frame snugly against the rim 12 when the frame is superimposed upon the 100 top of a can as shown in Fig. 3.

Extended through the slot 8 between the stretches 6 and 7 of the frame 5 contiguous to the projection 10 is a tapered pointed blade 13 having opposite beveled knife edges 14 and this blade is merged into a lever 15 provided with an eye or loop handle 16 at the end thereof remote from the blade 13. The blade 13 is swingingly supported upon a pivot 17 made fast in the stretches 6 and 7 of the frame 105 5, the said blade 13 being curved correspondingly to the curvature of the frame 5 and the

disposition of the slot 8 therein, so that on the swinging of the lever 15 in one position the said blade 13 can be moved into the slot in juxtaposition to the stretches 6 and 7 of the frame 5. The pivot 17 is positioned in proximity to the free end of the stretch 7 or in other words in close proximity to the projection 10.

The lever 15 is bent angularly in an outward direction relative to the axis of the pivot 17, so that the tool or opener can be readily manipulated by the user.

The projection 10 at its free end is formed with the circular notch 18 to conform to the mouth edge of a bottle C and the said extremity in its construction will constitute a jaw to engage with the cap D on the bottle C, in a manner as shown in Figure 4 of the drawing, so that by rocking the frame 5 upon the cap D on the bottle C the said cap can be extracted or removed from the mouth of the bottle as will be clearly apparent.

It will be apparent that the tool or opener is equally adaptable as a cap remover for bottles and the lever 15 by reason of its length thereof enables the free extraction or removal of the cap D from the bottle C with minimum exertion on the part of the user. This is also true when the tool or opener is used for opening the top of a can or other receptacle.

It will be obvious that by reason of the formation of the runner constituted by the frame 5 the latter can be reversed upon the can, so that the blade 13 can be actuated by the lever 15 to cut the top of the can in either direction according to the selection by the user of the tool or opener.

In the use of the tool or opener the pointed end of the blade 13 is pierced through the top of the can as is shown in Figure 2 of the drawing and the runner A is superimposed upon the top of the can so that the ear 9 will

abut the rim 12 of the can and the projection 10 will engage over said rim 12, so that by forcibly oscillating the lever 15 the top of the can will be severed either partially or wholly from the body of the can as will be clearly apparent.

The use of the tool or opener as a cap remover or extractor will be obvious from the showing of the mode of application of said tool or opener by Figure 4 of the drawing.

From the foregoing it is thought that the construction and manner of use of the tool or opener will be clearly understood and therefore a more extended explanation has been omitted.

What is claimed is:—

A can opener comprising a blade carrying runner formed from a single length of rigid material of strap like form bent on itself to provide a substantially segmental shaped frame closed at one end and open at the other and having a pair of spaced, concentrically arranged stretches one of greater length than and projecting beyond the free end of the other, an outwardly projecting curved ear integral with the free end of the longer of the said stretches and providing a combined guide and bearing, an outwardly extending angle shaped projection integral with the free end of the shorter of the said stretches and formed of an inner and an outer arm, said inner arm of less width than said outer arm thereby providing with the said short stretch a pair of grooves constituting seats, and a segmental shaped blade extending through said frame and pivoted to said stretches in proximity to said projection.

In testimony whereof, I affix my signature hereto.

JAMES S. PATTERSON.
